ROTARY CUTTER

John G. Antosh, Rhinelander, Wis.

Application June 6, 1950, Serial No. 166,368

2 Claims. (Cl. 164—70)

1

The present invention relates to cutters of the type having annular formation and supported upon a pair of parallelly disposed shafts with the blades in contacting relation, for cutting sheet material, either fabric or metal, including corrugated paper, when the same is fed between the blades and when the shafts rotate.

Due to the rigid connection of the cutter blades with the shafts, it often happens that the blades, during the cutting operation, exert an undue degree of pressure upon each other from a lateral direction with the resultant chipping off of the blades and damaging them and thereby completely destroying their usefulness. Such chipped cutting blades must be replaced with the new ones. The objectionable result mentioned is caused primarily by the shafts coming out of proper parallel alignment, which in turn may be caused by misalignment of the shaft supporting bearings due to one wearing off sooner than the other, or due to other causes.

Therefore, the principal object of the present invention is the provision of the yielding supporting means for the cutter blades, which may permit the cutter blades to yield, one away from the other, in a lateral direction, and axially of the shafts, without in any manner detracting from the proper operativeness of the cutter blades.

Another object of the present invention is the provision of an annular supporting member, with which a ring is associated, to which the cutter blade is rigidly affixed, with tensioning means provided between said supporting member and said ring for permitting the ring and cutter blade to yield or shift away from the end of the supporting member, whenever an undue pressure is exerted upon the cutter blade by the other cooperating cutter blade, for the purpose of obviating the undesirable result hereinabove specified.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application, and in which like designating characters refer to corresponding parts throughout the several views:

Fig. 1 is a side elevational view of a pair of shafts upon which a pair of cutters is supported in a mutually operative position, with the cutter blades in a contacting relation, ready to receive sheet of material for cutting the same;

2

Fig. 2 is an enlarged end elevational view of the cutter assembly;

Fig. 3 is a side elevational view thereof, partly in section, the section having been taken substantially on line 3—3 of Fig. 2;

Fig. 4 is a cross-sectional view, longitudinally of the annular supporting member, on line 4—4 of Fig. 3; and

Fig. 5 is a cross-sectional view transversely of the cutter, taken on line 5—5 of Fig. 2.

Referring in detail to the present drawing there is shown therein a pair of shafts 10 in a mutual parallel relation for supporting a pair of cutters, generally indicated by 11, in Fig. 1. Each of said cutters 11 includes an annular supporting member 12, which is clamped or otherwise rigidly affixed in an encompassing relation with shaft 10. One end of said annular supporting member 12 is provided with recess 13, located centrally of said supporting member 12. Coacting with that end of supporting member 12 is ring 14, which may be somewhat narrower than the width of said supporting member 12. Said ring 14 at one end thereof is provided with a reduced annular rib 15 which enters said recess 13 for sliding movement therewithin. Normally the end face of said rib 15 is in a spaced relation with the bottom body portion of said member 12, defining said recess 13, as is clearly seen in Figs. 3 and 5.

The side body portions of said ring 14, extending in lateral directions from said rib 15 define shoulders 16, which normally contact with and rest upon the adjacent body end portions of said annular member 12, adjacent said recess 13, for limiting further shifting movement of said ring 14 in the direction of said annular member 12.

The end face of said ring 14 is grooved for receiving therewithin knife or cutter blade 17 which is of an annular formation. The groove thereof effects an annular projecting flange 18, adjacent the inner periphery of said ring 14 for the purpose of maintaining said cutter blade 17 in a proper centered relation with ring 14 and supporting member 12.

The outer peripheral edge of said cutter blade 17 is bevelled, as at 19. The cutting edge of said cutter blade 17 is defined by the inner face of said cutter blade 17, which is in contact with ring 14, and of which the outer edge extends beyond said ring 14 in an outward direction, and by said bevel 19.

To maintain cutter blade 17 in a rigid relation with ring 14 a plurality of screws 20 is provided, the shanks of which are passed through said cutter blade 17 and are in a threaded engagement

with ring 14, as is clearly seen in Fig. 5. The heads of said screws 22 are provided with polygonal sockets 21 for reception therewithin of a socket wrench whereby said screws 22 may be either tightened or removed.

As seen in Fig. 1 the cutting edges of a pair of cooperating cutter blades 17 are in an overlapping relation, with the inner faces of a pair of cutter blades 17 in contact whereby said cutting edges may cut sheet of material when the same is fed between said cutter blades 17 when shafts 10 with cutters 11 rotate, each in an opposite direction.

For the purpose of rendering cutter blade 17 with its associated ring 14 yieldable away from supporting member 12 for the purpose specified, suitable mechanism for permitting such yielding is provided. This mechanism includes a plurality of screws 22 extended longitudinally of said supporting member 12 and passed from the opposite end thereof. Adjacent said opposite end of said supporting member 12 a plurality of bores 23 are made. Each screw 22 at its outer end is provided with cylindrical head 24 of a diameter substantially corresponding to the diameter of each bore 23.

Each of said bores 23, adjacent its inner end, communicates with a central, constricted opening 25, through which screw 22 freely passes and wherein the same may freely slide. The opposite end of each screw 22 is threaded for engaging ring 14. Interposed between head 24 and the shoulder in the body portion of member 12 defined by the bottom of said bore 23 and opening 25, is coil spring 26 normally compressed for the purpose of exerting pressure upon head 24 in order to drive rib 15 into recess 13 and shoulders 16 in contact with the adjacent lateral portions of said annular member 12, as is seen in Fig. 3.

Each head 24 is provided with a polygonal socket 21 for insertion therewithin of a socket wrench for the purpose of driving screw 22 in engagement with ring 14, or for disengaging the same therefrom. Obviously screw 22 may be driven nearer toward cutter blade 17 or farther away from it for the purpose of regulating the tension of coil spring 26.

When an unusual degree of pressure upon one cutter blade 17 is exerted by contacting the other cutter blade 17, due to causes hereinabove specified, the mutual pressure upon said cutter blades 17 will be engendered, of a degree which will be sufficient to cause the shifting movement of each cutter blade 17, with its cooperating ring 14 away from the adjacent end of annular supporting member 12. This in turn will cause the shifting movement of screw 22 within bore 23 and opening 25, against the tension of compressing coil spring 26, thereby bringing about mutual yielding of the two contacting cutter blades 17, without however interrupting the mutual contact therebetween, and without detracting from the cutting operation of the two cutter blades 17.

The unusual degree of pressure upon one cutter blade 17 by the other does not necessarily occur throughout the entire revolution of the two cutter blades 17. It may occur however at some one particular point of the peripheries thereof as they rotate. Therefore, when that point has passed cutter blades 17 and their cooperating rings 14 assume their normal positions, being forced into those positions by the pressure of coil springs 26 exerted upon screw heads 24.

Rib 15 constitutes therefore a guiding means for ring 14 and cutter blade 17 during their shifting either away from or toward said annular supporting member 12, thereby preventing the operative misplacement thereof from said member 12.

By virtue of the mechanism which permits mutual yielding of cutter blades 17, away from each other, and consequent shifting thereof away from supporting members 12, any possibility of the cutting edges of the cutter blades 17 being chipped or otherwise damaged will be effectively prevented.

Cutters 11 may be rigidly affixed to shafts 10 by any suitable means. If said cutters are each made in one piece, screws driven through supporting members 12 in a transverse direction for engaging shafts 10 will lock the cutters upon said shaft in a mutually adjusted relation for cutting operation. In the drawing another means for locking the cutters to shafts 10 is suggested. That latter means contemplates making cutter blades 17, rings 14 and supporting members 12 in two semi-annular pieces, with their free ends in mutual contact along lines 28. To effectively lock the two semi-annular pieces of the three parts hereinabove mentioned, rings 14 at their ends as well as supporting members 12 at their ends may be provided with tongue and lip joints 29.

That arrangement will effectively prevent shifting or misplacement of the two semi-annular halves of the parts in a transverse relation or in an axial relation with shafts 10. Screw 30 driven through the contacting ends of the semi-annular halves of the supporting member 12, that is in a transverse relation with the meeting plane along line 28, will not only bind the two semi-annular halves of the parts, but will also clamp the entire assembly to shaft 10. Recess 31 made adjacent one end of the semi-annular end of supporting member 12, and adjacent the periphery thereof, will permit the unobstructed engagement of the head of screw 30, as well as will accommodate the latter.

From the hereinabove description it will be seen that rib 15 sliding within recess 13 constitutes a guiding means for said ring 14 and cutter blade 17 in their shifting movement towards or away from supporting member 12, at the same time preventing the former from displacement on a transverse plane with relation to said supporting member 12.

Assuming that shafts 10 are in a horizontal position the contact point of a pair of cutter blades 17 will remain substantially on a vertical transverse plane of said shafts 10. Any deviation due to abnormal pressure by said cutter blades 17, one upon the other, will be permitted from said vertical transverse plane by the yielding connecting means, including screw 22, head 24 and coil spring 26.

It is further observed that the shifting of cutter blade 17 away from supporting member 12 due to an undue contactual pressure of one cutter blade 17 upon the other, will not disrupt the contactual relation of a pair of said cutter blades 17, during the operation of a pair of cutters 11, due to the action of spring 26, which, through head 24 at all times draws said cutter blades 17 towards their respective supporting members 12.

Although in Fig. 1 both cooperating cutters as shown are yieldable, it is understood that good results will be obtained when only one

cutter is yieldable and the other is rigid, because for all practical purposes when there is an undue degree of pressure between the two cutter knives the yieldable one will always yield under the pressure notwithstanding the fact that the other cutter is rigid and unyielding.

While there is described herein a preferred embodiment of the present invention, it is nevertheless to be understood that minor changes may be made therein without departing from the spirit and scope of the invention as claimed.

What I claim as new is:

1. A rotary cutter comprising an annular supporting member, a cutter blade, a blade mounting member, one end of said supporting member being provided with an annular continuous recess, a reduced annular rib formed at one end of said blade mounting member, said rib entering said recess for sliding movement axially of said supporting member, said cutter blade being rigidly affixed to the opposite end of said blade mounting member, and yieldable connecting means between said supporting member and said blade mounting member for normally maintaining said blade mounting member in contact with said supporting member, a pressure exerted upon said cutter blade in a lateral direction away from said supporting member permitting said connecting means to yield for shifting said blade mounting member away from said supporting member, during the shifting movement of said blade mounting member said rib sliding within said recess for guiding said blade mounting member in its shifting movement with relation to said supporting member.

2. A rotary cutter comprising a pair of parallelly disposed shafts, a pair of annular supporting members each in a rigid encompassing relation with one of said shafts, a pair of annular cutter blades, a pair of annular blade mounting members, each of said cutter blades being rigidly

affixed to one end of each of said blade mounting members, said cutter blades being in a mutual overlapping lateral contactual relation on a plane substantially transverse with relation to said shafts, one end of each of said supporting members being provided with an annular continuous recess, a reduced annular rib formed at the opposite end of each of said blade mounting members, each of said ribs entering one of said recesses whereby said blade mounting members are capable of sliding movement longitudinally with relation to said supporting members, a plurality of screws passed longitudinally of said supporting members for engaging each of said ribs, heads formed at the free ends of said screws, said supporting members being provided with bores of diameters substantially corresponding to the diameters of said heads, said screws and said heads being positioned within said bores for sliding movement, and coil springs encompassing said screws and interposed between the body portion of each of said supporting members and said heads, said coil springs exerting pressure upon said heads for normally maintaining said blade mounting members in contact with said annular supporting members, any undue lateral mutual pressure upon said cutter blades causing said ribs to shift within said recesses for bringing said blade mounting members out of contact with 30 said supporting members.
